MINE MACHINE

Edwin P. Stenger, Cincinnati, Ohio, assignor to
The Cincinnati Mine Machinery Company, Cincinnati, Ohio, a corporation of Ohio

Application May 28, 1942, Serial No. 444,849

11 Claims.

(Cl. 74—254)

My invention relates to cutter chains for mining machines and particularly to the pintle which joins the bit carrying link to the connecting links and means for fastening the same.

Inasmuch as cutter chains of the above type are subject to very heavy and rough wear, it has been found advisable to position the pintles in the side bars of the bit carrying link so that they will not revolve. It is also desirable to have these pintles so arranged as to be easily removable and insertable for repairs while the chain is on the job in a mine.

It is an object of my invention to provide a pintle positioned in the side bars of the bit carrying link which is not rotatable even under the heaviest kind of wear, and wherein the rotation of the pintle is prevented by shoulders similar to that shown in my Patent No. 2,280,502, issued April 21, 1942, and wherein I provide means which hold the pintle in place against longitudinal movement and which means permit the easy removal and insertion of the pintle under the most unfavorable conditions normally met in a coal mine.

These other objects of my invention which will be set forth hereinafter or will be apparent to one skilled in the art after reading the specifications, I accomplish by that certain construction and arrangement of parts of which I shall now describe an exemplary embodiment. Reference is now made to the drawing which forms a part thereof and in which:

Figure 1 is a side elevation of a cutter chain including a bit carrying link and connecting links.

Figure 2 is a section on the section line 2—2 of Figure 1.

Figure 3 is a perspective view of the pintle shown in Figures 1 and 2.

Figure 4 is a perspective view of one of the plugs used in connection with the pintle shown in Figure 3.

Figure 5 is a perspective view of a modifying pintle.

Figure 6 is a cross-section similar to that shown in Figure 2, but with one of the plugs knocked out.

Briefly, in the practice of my invention, I provide a pintle having a cross-section defined by a portion of a circle and joined by a cord and similar to that shown in my Patent No. 2,280,502, issued April 21, 1942. The aligned apertures in the side bars for receiving the pintle are similarly configured so that the pintle may not revolve. The pintle is so positioned that the circular portion of the surface is positioned against the

circular aperture or journal in the connecting link; so that all of the friction between the pintle surface and the bearing of the connector link is carried by the circular portion of the pintle.

5 In order to prevent my pintle from sliding longitudinally out of the apertures of the side bars, I provide tapered hollow channels running longitudinally through the pintle and tapered plugs which are insertable in the channel ends. The pintle is slit at both of its ends and when the pintle is in position, tapered plugs driven into the tapered channel expand the ends of the pintle and thus frictionally lock the ends in the side bars. One of the plugs has a longitudinal hole therein which permits the insertion of a rod for driving out the other plug when it is necessary to remove the pintle. After one of the plugs has been driven out, the rod is inserted in the space previously occupied by that plug, and the first 10 plug may be driven out.

Referring to the drawing, I provide the usual bit carrying link 1 having the side bars 2. Connecting the bit carrying links of the cutter chain is the usual connecting link 3, which has a circular bearing as is well known in the art. My pintle 4 consists of a circular rod with a flattened portion or chord 5. Tapered hollow channels 13 run longitudinally through the pintle with the cross-section of the channel diminishing from both ends of the pintle towards the center. I provide tapered plugs 14 and 14a which are insertable in the end of the channels 13. The pintle is slit as at 15.

The pintle 4, as is apparent, may be inserted from either side of the side bars and is self-aligning. When the pintle is in position, the plugs 14 and 14a are driven into the channels 13 in the ends of the pintle which expand the ends due to the tapering of the channels 13 and the slits 15, and spread apart the ends and wedge them against the aperture in the side bars 2. To remove the pintle from the side bar, a rod 20, of less diameter than the aperture in the plug 14, is inserted through the aperture in the plug 45 so as to contact the inner face of the second plug 14a and by driving the rod, the plug 14a is driven out of the pintle, as is apparent in Figure 6. After the plug 14a is removed, the rod is then inserted in the aperture from which plug 14a was driven, and the other plug 14 may be driven from the pintle. This permits the contracting of the ends of the pintle 4 and permits the easy longitudinal movement of the pintle for removing the same from the chain in either direction.

55 In the modification shown in Figure 5, the

pintle has a single longitudinal slot 21. The slot 21 is cut through from the face 22 of the pintle its whole length and down to the tapered channels 13. This pintle is inserted in the same manner as heretofore described and the same plugs 14 and 14a are used to expand the pintle. In this case, it will be noted that the slot 21 is so positioned in reference to the position of the pintle in the cutter chain that no friction or wear is presented to the surface of the pintle which contains the slot.

From the above it is apparent that I have provided a pintle which may be readily removed and inserted in a cutter chain from either side of the chain and which is so configured as to parts, etc. that the positioning, insertion and removal of the same may be easily carried on in the dark and under the most unfavorable conditions existent in a coal mine, but which when once inserted and expanded will not slide nor revolve, and which will consequently promote long chain life and efficient performance.

It is to be understood that modification may be made in my invention without departing from the spirit thereof and I do not intend to limit myself otherwise than as pointed out in the claims which follow:

Having thus described my invention what I claim as new and desire to secure by Letters Patent, is:

1. In combination with a bit carrying link of a mining machine cutter chain, and a connecting link, one of said links having spaced side bars between which the connecting link is introduced, said connecting link having a circular aperture, and a pintle mounted in the side bars and passing through said circular aperture, said pintle having a flattened portion, and at least one of the side bars having an aperture for the pintle and which includes a shoulder to engage the flattened portion, thereby preventing the pintle from rotation, said pintle being longitudinally slidable through at least two of said apertures and means for securing the pintle against endwise movement comprising slits in the ends of the pintle, a hole through the pintle from end to end, and tapered plugs to enter the ends of the pintle to expand same, one of said plugs having a hole therein sufficient to receive a tool for driving out the other plug.

2. For use in combination with a mining machine cutter chain having links including side bars and connecting links positioned within the side bars, a pintle having a constant outside cross-section the outline of which is the same as the aligned apertures of the side bars, said pintle having a longitudinal hole therein from end to end, tapered plugs to enter the ends of said hole to expand the ends of the pintle and said pintle having at least one slot to permit the expansion of the same.

3. For use in a mining machine chain, a pintle having a longitudinal passage therein, said passage commencing at one end of said pintle and tapering inwardly, at least one slot in the end of said pintle and communicating with said passage, and a tapered plug for insertion in said passage for expanding said pintle and to prevent longitudinal movement of the pintle.

4. For use in a mining machine chain, a pintle having a longitudinal circular passage therethrough from end to end, the ends of said passage being of a given cross-sectional area and tapering to a smaller cross-sectional area at the center, tapered plugs for insertion in the ends of said passage, said pintle having slit ends so as to permit expansion of the same upon insertion of said plugs.

5. For use in a mining machine chain, a pintle having a longitudinal circular passage therethrough from end to end, the ends of said passage being of a given cross-sectional area and tapering to a smaller cross-sectional area at the center, tapered plugs for insertion in the ends of said passage, said pintle having slit ends so as to permit expansion of the same upon insertion of said plugs, one of said plugs having a hole therein sufficient to receive a tool for driving out the other plug.

6. For use in a mining machine chain, a pintle having a longitudinal circular passage therethrough from end to end, the ends of said passage being of a given cross-sectional area and tapering to a smaller cross-sectional area at the center, tapered plugs for insertion in the ends of said passage, means in said pintle for permitting expansion of at least the ends thereof upon insertion of said plugs.

7. For use in a mining machine chain, a pintle having a longitudinal circular passage therethrough from end to end, the ends of said passage being of a given cross-sectional area and tapering to a smaller cross-sectional area at the center, tapered plugs for insertion in the ends of said passage, said pintle having a longitudinal slot in the side thereof communicating with the passage to permit expansion of the pintle upon insertion of said plugs.

8. For use in a mining machine chain, a pintle having a longitudinal passage therein, said passage tapering from each end toward the center, a flattened portion on the side of said pintle and running substantially its full length, a slot in said flattened portion communicating with said passage and tapered plugs for insertion in said passage ends for expanding said pintle to prevent longitudinal movement thereof.

9. For use in a mining machine, a pintle in the form of a cylinder having a longitudinal flattened portion and an internal channel throughout its length, a longitudinal groove in the flattened portion and communicating with said channel, and means for expanding said pintle.

10. A pintle comprising a circular bar having a longitudinal flat face and a channel running therethrough, a slot connecting said face with said channel and wedging means for expanding said pintle.

11. For use in a mining machine, a pintle in the form of a cylinder having a longitudinal flattened portion and an internal channel throughout its length, a longitudinal groove in the flattened portion and communicating with said channel, and means comprising a wedge for expanding said pintle.

EDWIN P. STENGER.
